UNITED STATES PATENT OFFICE

ALBERT F. BARNES, DECEASED, LATE OF BROOKLYN, NEW YORK, BY ANNABEL BARNES,
EXECUTRIX, OF BROOKLYN, NEW YORK

APPARATUS FOR THE FORMATION OF CONCRETE PILES IN SITU

Application filed June 3, 1929. Serial No. 367,942.

This invention relates to apparatus for use in the formation of concrete piles in situ, and, more particularly, to core head constructions and to correlated improvements and discoveries appertaining thereto.

An object of the invention is to provide an improved construction at the upper end of a collapsible core, whereby the strain during driving is efficiently distributed, and whereby during lifting, the weight of the core is removed from the collapsing links and taken up by associated parts of the core head structure.

Another object is to provide apparatus of the character described which is of simple and sturdy construction, and which operates efficiently and with freedom from mechanical defects.

Other objects of the invention will in part be obvious and will in part appear herein-after.

The invention accordingly comprises the features of construction, combinations of elements, and arrangement of parts, which will be exemplified in the constructions herein-after set forth and the scope of the application of which will be indicated in the claims.

For a fuller understanding of the nature and objects of the invention, reference should be had to the following detailed description taken in connection with the accompanying drawings, in which:

Figure 1 is a longitudinal section of a collapsible core embodying the invention, showing the core inserted in a pile casing, a longitudinal portion of the core being broken away;

Fig. 2 is a transverse section in the direction of the arrows along the line 2—2 in Fig. 1;

Fig. 3 is an enlarged detail sectional view of the core-head construction;

Fig. 4 is a plan view thereof; and

Fig. 5 is a side elevation of the core-head viewed at right-angles to Fig. 3, and showing the lower portion of a hammer element mounted thereon.

The exemplified apparatus comprises a collapsible core, indicated generally at 10, of a type suitable to be sunk into the ground either alone or in conjunction with thin sheet metal

or similar shell, such as shown at 11, to form a cavity into which concrete may be poured for the formation of a concrete pile or the like. The exemplified core comprises a center bar 12 and a plurality of core leaves 13 separated longitudinally so as to permit the same to be expanded against the inner surface of the shell during driving, and to be collapsed when the core is to be withdrawn, the core leaves being connected to the center bar by suitable toggle links, such as indicated at 14. In order to press the core leaves into their expanded position, the center bar carries a series of wedge members 15 having upwardly and outwardly inclined surfaces, which are adapted to seat against the surfaces of co-operating wedging elements 16 on the core leaves.

The driving is ordinarily effected by the blows of a hammer which can be suitably applied to a driving-cap 17 which is preferably mounted at the upper end of the center bar as by means of screw-threads 18. In order that the driving force may be evenly transmitted to the core leaves during driving, without danger of injury thereto, the invention contemplates the provision of a suitable element, which is designated herein by the general term "driving-plate", and which is exemplified at 19. This plate is interposed between the driving-cap and the core leaves, and is adapted to transmit and distribute the force of the hammer blows from the driving-cap to the top of the core leaves when the latter are in expanded position. The driving-plate 19, as exemplified, fits about the downwardly extending stem 20 on the driving cap and is slidably keyed thereto, as indicated at 21. In order positively to limit the expansion of the core leaves at their upper end, the driving plate is formed, in the present instance, with a downwardly extending external flange 22 which surrounds the upper ends of the core leaves so as to limit their expanding movement, preferably at a time when the links 14 are in an approximately horizontal position.

The driving plate 19 is held against longitudinal movement with respect to the core leaves by means of a series of pins 23 which

are adapted to extend into recesses 24 formed in a downwardly extending flange 25 on the driving head, the pins being sufficiently short so as to permit radial movement of the core leaves as the same are collapsed. In order to draw the driving plate and the core leaves upwardly when the center bar has been raised somewhat and the leaves have been collapsed to such an extent that they are free from frictional engagement with the pile shell, the internal flange 25 on the driving plate is provided with a downward extension as at 26, terminating at a point slightly removed from the upper surface of the upper wedge member 15, there being thus provided a construction which combines simplicity with sturdiness, and which effectively assures the withdrawal of the core leaves without danger of injury to the leaves or to the toggle links.

With a view to preventing relative longitudinal movement of the driving cap and the driving plate during the driving operation, there is provided on the driving cap a plurality of latches 27 having forked upper ends, and the driving plate is formed with recesses, indicated at 28 to receive these latches.

In order positively to separate the center-bar and the core leaves to break the clamping action of the wedging surfaces, after the driving operation is complete, the driving-cap carries a transverse shaft 28', on the ends of which there are rotatably mounted the arms 29 of a U-shaped member 30, the free ends of the arms 29 being formed with cam surfaces 31 adapted to bear against the upper surface of the driving-plate when the bow 32 of the U-shaped member is moved upwardly. In operation, the latches 27 are detached and a line secured to the bow 32 of the U-shaped member, and upward pull applied. The U-shaped member is thus swung so that the cam surface 31 presses downwardly upon the driving-plate so as to cause relative longitudinal movement between the driving-plate with its attached core leaves, and the driving-cap.

There is thus provided a simple construction which is composed of a relatively small number of sturdy parts, and which can be operated with a maximum of ease and with a minimum of danger of injury to the core leaves and to the other parts the repair or replacement of which is attended with considerable difficulty.

Since certain changes may be made in the above construction and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention

herein described, and all statements of the scope of the invention which as a matter of language might be said to fall therebetween.

Having described the invention, what is claimed as new and desired to be secured by Letters Patent is:

1. Pile-driving apparatus, comprising a center bar, core leaves collapsibly associated with said center bar, a driving cap attached to said center bar, and a driving plate interposed between said driving cap and said core leaves, said driving plate and said core leaves being movable as a unit longitudinally of said center bar.

2. Pile-driving apparatus, comprising a center bar, core leaves collapsibly associated with said center bar, a driving cap attached to said center bar, and a driving plate interposed between said driving cap and said core leaves and mounted for longitudinal movement with respect to said center bar.

3. Pile-driving apparatus, comprising a center bar, core leaves collapsibly associated with said center bar, a driving cap attached to said center bar, a driving plate interposed between said driving cap and said core leaves and means to prevent relative longitudinal movement of said driving plate and said core leaves, said center bar being adapted to spread said core leaves when the center bar is moved downwardly with respect thereto, and said driving plate being formed with means to limit the spreading movement of said core leaves.

4. Pile-driving apparatus, comprising a center bar, core leaves collapsibly associated with said center bar, a driving cap attached to said center bar, and a driving plate interposed between said driving cap and said core leaves, said plate and said leaves being movable as a unit longitudinally of said bar, said driving plate being formed with an annular flange surrounding the upper ends of the core leaves at all times during the operation of the apparatus.

5. Pile-driving apparatus, comprising a center-bar, core leaves collapsibly associated with said center-bar, a driving-cap attached to said center-bar, a driving plate interposed between said driving-cap and said core leaves, and means for preventing longitudinal movement between said driving plate and said core leaves while permitting radial movement of the core leaves.

6. Pile-driving apparatus, comprising a center-bar, core leaves collapsibly associated with said center-bar, a driving-cap attached to said center-bar, a driving-plate interposed between said driving-cap and said core leaves, means for preventing longitudinal movement between said driving-plate and said core leaves while permitting radial movement of the core leaves, and cooperating means on said driving-plate and on said center-bar for limiting the relative longitudinal movement

of the same, whereby lifting force applied to the center bar may be transmitted directly to the driving plate.

7. Pile-driving apparatus, comprising a center-bar, core leaves collapsibly associated with said center-bar, a driving-cap attached to said center-bar, a driving-plate interposed between said driving-cap and said core leaves, means for preventing longitudinal movement between said driving-plate and said core leaves while permitting radial movement of the core leaves, said driving-plate being formed with an internal annular flange and said center-bar being formed with means extending beneath said annular flange and spaced therefrom just sufficiently to contact therewith when said leaves are in collapsed position, whereby lifting force applied to the center bar is transmitted to the driving plate and thence to the core leaves.

8. Pile-driving apparatus, comprising a center bar, wedging members on the center bar, core leaves collapsibly associated with said center bar and having cooperating wedging elements thereon, a driving plate at the upper end of said core leaves, means for preventing longitudinal movement of said core leaves with respect to said driving plate while permitting radial movement of the core leaves, and an element extending downwardly from said driving plate within said core leaves to a point above the upper one of said wedging members, said downwardly extending element being spaced from said upper wedging member a distance such that said wedging member will contact with said downwardly extending element when the wedging element is moved upwardly just sufficiently to permit the collapse of the core leaves, whereby said core leaves, when collapsed, may be supported from said center bar through the medium of said driving plate.

9. Pile-driving apparatus, comprising a center bar, collapsible core leaves, collapsing links between said center bar and said core leaves, a driving cap, a driving plate interposed between said driving cap and said core leaves and mounted on said core leaves, and cooperating means on said driving plate and said center bar for effecting the withdrawal of said core leaves with said center bar before the longitudinal movement of the center bar places a withdrawing strain on said links.

55 10. Pile-driving apparatus, comprising a center bar, collapsible core leaves, collapsing links between said center bar and said core leaves, a driving cap, a driving plate interposed between said driving cap and said core leaves and mounted on said core leaves, said driving plate being formed with an internal annular flange, and an element on said center bar and adapted to contact with said flange to effect withdrawal of the core leaves with the center bar after said links have effected

the collapse of the core leaves and before any strain is placed thereon.

11. Pile-driving apparatus, comprising a center bar, core leaves collapsibly associated with said center bar, a driving cap attached to said center bar, a driving plate interposed between said driving cap and said core leaves, means for preventing longitudinal movement between said plate and said leaves while permitting radial movement of said leaves, and means for releasably connecting said driving cap to said driving plate.

12. Pile-driving apparatus, comprising a center bar, core leaves collapsibly associated with said center bar, a driving cap attached to said center bar, and a driving plate interposed between said driving cap and said core leaves, means for preventing longitudinal movement between said plate and said leaves while permitting radial movement of said leaves, a plurality of latches carried by said driving cap and adapted to releasably hold said driving plate against movement, said driving plate being formed at its outer surface with recesses adapted to receive said latches.

13. Pile-driving apparatus, comprising a center bar, core leaves collapsibly associated with said center bar, a driving cap attached to said center bar, a driving plate interposed between said driving cap and said core leaves and movable relatively to the center bar, means for preventing longitudinal movement between said plate and said leaves while permitting radial movement of said leaves, and lever means carried by said driving cap and adapted to bear against the upper surface of said driving plate for separating said center bar from said core leaves to collapse the core leaves.

14. Pile-driving apparatus, comprising a center bar, core leaves collapsibly associated with said center bar, a driving cap attached to said center bar, a driving plate interposed between said driving cap and said core leaves and movable relatively to the center bar, means for preventing longitudinal movement between said plate and said leaves while permitting radial movement of said leaves, a transverse shaft carried by said driving cap, and a U-shaped lever element mounted for rotation on said shaft and formed with a pressure surface adapted to press against the upper surface of the driving plate when upward pressure is applied to the bow of the U.

15. Pile-driving apparatus, comprising a center bar, core leaves collapsibly associated with said center bar and adapted to be wedged outwardly when said center bar is moved downwardly with respect thereto, a driving cap attached to the upper end of said center bar, a transverse shaft on said driving cap, a driving plate interposed between said driving cap and said leaves and movable relatively to said bar, means for preventing longitudinal movement between said plate and said

leaves while permitting radial movement of said leaves, a U-shaped lever mounted for rotation on said transverse shaft and adapted, when pressure is applied to the bow of the U, to impart relative longitudinal movement to said center bar and said core leaves to break the wedging fit therebetween.

16. Pile-driving apparatus comprising a center bar, a plurality of core leaves surrounding said center bar and adapted to move radially and longitudinally thereof, cooperating wedging members on said center bar and core leaves respectively, a driving plate disposed above said core leaves, means for preventing longitudinal movement between said plate and said leaves while permitting radial movement of said leaves, and an annular flange extending downwardly from said driving plate and surrounding said core leaves when the same are in both collapsed and expanded position and adapted to limit the expansion of said core leaves.

17. Pile-driving apparatus comprising a center bar, a plurality of core leaves surrounding said center bar and adapted to move radially and longitudinally thereof, cooperating wedging members on said center bar and core leaves respectively, a member disposed above said core leaves and provided with an annular rim surrounding said core leaves at all times during the operation of said apparatus, and means for preventing longitudinal movement between said member and said leaves while permitting radial movement of said leaves.

18. Pile-driving apparatus comprising a driving cap, a center bar carried thereby, expandable and collapsible core leaves surrounding said center bar, a driving plate disposed between said driving cap and the upper ends of said core leaves, said driving plate and said core leaves being movable as a unit relative to said center bar, and a downwardly extending flange on said driving plate surrounding the upper ends of said core leaves for limiting the expansion thereof.

19. Pile-driving apparatus comprising a center bar, a plurality of core leaves surrounding said center bar, pivoted link connections between said core leaves and said center bar, cooperating wedging members carried by said center bar and said core leaves, a driving plate disposed above said core leaves and movable longitudinally therewith with respect to said center bar, and cooperating means on said center bar and said driving plate for lifting said driving plate and said core leaves upwardly to the end of the collapsing movement of the core leaves whereby lifting strain on said links is avoided.

20. Pile-driving apparatus comprising a center bar, a plurality of core leaves surrounding said center bar, a driving plate disposed about said core leaves and movable

longitudinally therewith with respect to said center bar, cooperating wedging members on said core leaves and said center bar for expanding said core leaves, means on said driving plate for limiting the expansion of said core leaves, cooperating means on said center bar and said driving plate for lifting said driving plate and said core leaves when the core leaves are collapsed, and cam means associated with said center bar and operable against the upper surface of said driving plate for breaking wedging action of said wedging members to permit collapsing of the core leaves.

21. In an apparatus of the character described, a central unit comprising a longitudinally-extended bar having longitudinally-spaced wedging members thereon and an outer unit comprising a driving plate and a plurality of expandable and collapsible core leaves suspended therefrom, means for preventing longitudinal movement between said plate and said leaves while permitting radial movement of said leaves, each of said core leaves being provided with longitudinally-spaced wedging members adapted to cooperate with the aforesaid wedging members, said units having a limited longitudinal movement with respect to each other.

22. Pile-driving apparatus comprising a center bar, a plurality of core leaves surrounding said center bar, pivoted link connections between said core leaves and said center bar, cooperating wedging members carried by said center bar and said core leaves, a driving plate disposed above said core leaves and movable longitudinally therewith with respect to said center bar, means for preventing longitudinal movement between said driving plate and said core leaves while permitting radial movement of the core leaves, and cooperating means on said center bar and said driving plate for lifting said driving plate and said core leaves upwardly to the end of the collapsing movement of the core leaves whereby lifting strain on said links is avoided.

In testimony whereof I affix my signature.
ANNABEL BARNES,
Executrix of the Last Will and Testament of Albert F. Barnes, Deceased.
